DOOR OPERATED SWITCH

Filed March 12, 1928

FIG. 1

FIG. 2

FIG. 4

FIG. 3

Inventor
J.E. Beauchamp
By
Quinnigan,
Attorney.

UNITED STATES PATENT OFFICE.

JOSEPH ERNEST BEAUCHAMP, OF MONTREAL, QUEBEC, CANADA.

DOOR-OPERATED SWITCH.

Application filed March 12, 1928. Serial No. 260,821.

The present invention relates to improvements in a "Door operated electric switch or the like," which is hereinafter fully described and claimed, and is illustrated in the accompanying drawings, in which:—

Figure 1 is a longitudinal sectional view through a switch according to the invention, when in its non-operative position.

Figure 2 is a similar view to Figure 1, when the switch is in its operative position.

Figure 3 is a longitudinal sectional plan view of the switch, and,

Figure 4 is an end view of the door operated pawl.

Like numerals of reference indicate corresponding parts in each figure.

Referring to the drawings:—

1 is the switch base member having on one side thereof the recessed member 2 and on the opposite side the outwardly projecting brackets 3 and the lugs 4. In the brackets 3 is mounted the switch element 5, of the well known pull chain type, and 6 is the usual pull chain. Immediately below said switch element, and in alignment therewith, is provided a bracket 7 preferably integral with said base 1 and at right angles thereto. On said bracket 7 is pivotally mounted the pawl 8 which consists of an elongated member having a semi-circular head 9 provided with a circumferential recess 10, in which its pull chain 6 is secured by means of the pin 11.

In one side of the recessed member 2, may be provided an elbow or tubular extension 12, through which the electrical conductors 13 and 14 project and are connected to their respective poles 15 and 16 in the switch 5.

The pawl 8 is actuated by a lug 17, which is secured upon the upper edge of the door 18, (shown in dot and dash lines in the drawings) which upon opening the door, will cause the pawl 8 to be tilted, as disclosed in Figure

2 of the drawings, thus pulling the chain 6 and operating the switch to complete an electric circuit, which will light an electric lamp. 45 To break the circuit, the door must be opened a second time, which causes the pawl 8 to pull a second time, the pull chain 6. The chain 6 being located in the recess 10 in the head 9 of the pawl 8, is thus prevented from falling-off said pawl. When closing the door, the lug 17 pushes the pawl backwards, without however, operating the pull chain 6.

The switch element 5 is covered by a casting 19 which is provided with a slot 20 through which the pawl 8 projects, and suitably secured to the base, thus providing a switch of neat appearance, and cheap to manufacture.

What I claim as my invention is:—

A device of the character described, adapted to be operated in combination with a door, comprising a base member, brackets projecting outwardly from said base, a switch element of the pull chain type secured in said brackets and a pull chain projecting therefrom, a bracket projecting outwardly from said base and located below the aforesaid brackets, a pawl pivotally mounted upon said bracket, said pawl having a semi-circular 70 head provided with a circumferential recess in which is secured the free end of said pull chain, means to electrically connect said switch element to an electric circuit, a cover over said switch element having a slot 75 through which projects the lower end of said pawl, and means adapted to be secured to said door whereby upon opening said door, said pawl will be operated to pull a chain, substantially as described.

Signed at Montreal, Quebec, Canada, this 18th day of October, 1927.

JOSEPH ERNEST BEAUCHAMP.
